UNITED STATES PATENT OFFICE

ANNA ALOISI, OF BROOKLYN, NEW YORK

DESIGN FOR A LAMP

Application filed July 24, 1929. Serial No. 32,194. Term of patent 7 years.

To all whom it may concern:

Be it known that I, ANNA ALOISI, a citizen of the United States, residing in New York city, borough of Brooklyn, in the county of Kings and State of New York, have invented a certain new, original, and ornamental Design for Lamps, of which the following is a specification, reference being had to the accompanying drawing, forming a part thereof, and of which—

I claim:

The ornamental design for a lamp as shown.

ANNA ALOISI.
